Primary Examiner — S. Bryan Reinholdt, Jr.*Assistant Examiner* — Kaitlan Walker(74) *Attorney, Agent, or Firm* — KW Law, LLP(57) **CLAIM**

The ornamental design of an ammunition magazine, substantially as shown and described.

DESCRIPTION

FIG. 1 is a top, front perspective view of an ammunition magazine in accordance with the present design.

FIG. 2 is a front view thereof;

FIG. 3 is a back view thereof;

FIG. 4 is a first side view thereof;

FIG. 5 is a second side view thereof;

FIG. 6 is a top view thereof; and,

FIG. 7 is a bottom view thereof.

The broken lines in the Figures show portions of the ammunition magazine which form no part of the claimed design.

1 Claim, 6 Drawing Sheets(56)
